CLARK H. POOL, OF BINGHAMTON, NEW YORK, ASSIGNOR TO STAR ELECTRIC COMPANY, A CORPORATION OF NEW YORK.

SIGNALING SYSTEM.

1,124,799.

Specification of Letters Patent.

Patented Jan. 12, 1915.

Application filed January 12, 1914. Serial No. 811,538.

To all whom it may concern:

Be it known that I, CLARK H. POOL, a citizen of the United States, residing at Binghamton, in the county of Broome and 5 State of New York, have invented a new and useful Signaling System, of which the following is a specification.

My invention relates to improvements in fire alarm signaling systems such as may be 10 used in factory buildings or in large manufacturing plants.

In these factory systems suitable translating devices are distributed at various points about the protected premises to warn the occupants so they may have an opportunity 15 to escape in case of fire. For simplicity these devices are called "fire warning signals" throughout this specification and accompanying claims. Other devices are located at points which may be convenient to 20 notify the fire fighting force and these are herein called "fire fighting signals." Telegraphic transmitting mechanism is provided at a plurality of stations and any station 25 may be operated to call the fire fighting force to that particular station and at the same time to warn the occupants of the building. It is often desired to provide some 30 means of selection by which it may be possible to test the different signal devices and to have fire drills of parts of the system or in parts of the factory without operating the entire system.

The objects of my improvement are—to 35 provide a system in which the circuits may be arranged at any station so that the transmitting mechanism at that station may cause operation of only the fire warning signals, when, for example, a fire drill of the entire 40 premises is desired without calling out the fire fighting force—to provide a system in which the circuits may be arranged at any station so that the transmitting mechanism at that station may cause operation of only 45 the fire fighting signals, when, for example, a drill of the fire fighting force is desired without alarming the occupants of the premises—to provide a system in which the circuits may be arranged at any station so that 50 the transmitting mechanism at that station may cause operation of the fire warning signals and of the fire fighting signals, when, for example, an actual fire occurs—to provide a system in which the circuits may be 55 arranged at any station so that the transmit-

ting mechanism at that station may cause operation of only the fire warning signals associated with that station, when, for example, a fire drill of one section of the premises is desired without calling out the fire 60 fighting force or alarming the occupants of the rest of the premises.

In the ordinary "series circuit" in which the strokes of the alarm are given upon the breaking of the circuit, it is practically impossible to secure a sound loud enough to be heard above the usual factory noise without the use of devices such as electromechanical gongs, etc., or devices operated by batteries in local circuits controlled by relays, both of 65 these expedients being expensive not only in first cost but also in maintenance and also introducing additional chances of failure of operation when most needed. The patent to C. E. Beach, May 20, 1913, No. 1,062,381 70 shows a method of connecting "open circuit" signal devices in a series circuit so arranged as to secure the passage of a normal test current through them without the use of an excessive amount of energy while the 75 telegraphic transmitting mechanism is so connected that when it is operated the flow of current through the signal devices is reversed and also greatly increased, thus permitting efficient operation directly from the 80 main source of current.

While the improvements herein shown and described are applied to a system similar to that shown in the patent above referred to, I desire not to be limited to the 90 particular construction herein shown, as changes may be made therein without departing from the spirit of the invention.

The objects above mentioned are attained by the means illustrated in the accompanying drawing, in which similar reference characters refer to similar parts throughout.

As shown, there are four stations, A, B, C and D. A source of current 1 is provided to supply the necessary energy for the operation of the system. One or more fire 100 warning signals may be associated with each of the stations, these signals being represented by the single stroke bell 2 at station D, and at the other stations by suitable 105 devices 3. Fire-fighting signals 4 may be located at the apparatus stations. At the end of the system opposite to source 1 are two electromagnets 5 and 6. These magnets control the circuit of alarm device 7 110

and battery 8. At each station telegraphic transmitting mechanism of any suitable type may be installed, and only those parts necessary to illustrate the operation of my system are shown. The wheel 9 operates the signaling lever 10. Two circuit controllers are associated with the signaling lever and the springs 11, 12 and 13, 14 of each circuit controller are closed when the signaling lever is raised and are opened when the signaling lever drops. Suitable switch mechanism for controlling the selection of the different circuit conditions is associated with each telegraphic transmitting mechanism. This switch mechanism comprises two switch arms 15 and 25 connected for simultaneous action by a bar of insulating material, the arm 15 being adapted to engage contacts 16, 17, 18 and 19 and arm 25 being adapted to engage contacts 26, 27, 28 and 29. Spring 11 is connected to wire 20, spring 12 to arm 15, spring 13 to arm 25, spring 14 to wire 30, contacts 16 and 17 to wire 24, contact 18 to resistance 31 which is connected to contact 27 and wire 22, contact 19 to resistance 32 which is connected to wire 23 at one side of the fire warning signal or signals associated with that station, contacts 26 and 28 to wire 21, and contact 29 to wire 23 at the other side of the associated fire warning signal.

Current normally flows from the source 1 through wire 20, magnet 5, wire 21, fire fighting signals 4, wire 22, wire 23, through fire warning signals 2 and 3 therein, wire 24, magnet 6, and wire 30 to source 1. Trouble magnets 5 and 6 are so wound that their armatures will be attracted, while the signals 2, 3 and 4 are so wound that their armatures will not be moved by this current, the resistance of said magnets 5 and 6 being so high that current does not pass through this path in sufficient quantity to operate the signal receiving devices. As long as the armatures of both magnets 5 and 6 are attracted, alarm device 7 does not sound. If the series circuit should be broken or the source 1 should fail, the retraction of the armatures of magnets 5 and 6 will close the circuit of the alarm to indicate trouble.

Station A shows the switch mechanism in such position that the telegraphic transmitting mechanism thereat may cause operation of the fire fighting signals only. When the springs 11, 12 and 13, 14 are closed, the circuit from source 1 is to wire 20, to the operating box, where the circuit divides into two paths; (1) from wire 20 to spring 11, spring 12, arm 15, contact 18, resistance 31 (which is approximately equal to the total resistance of the devices 2 and 3 and is used in this path as a substitute for them), to wire 22, where this circuit divides into two paths: (a) to the left in wire 22, fire fight-

ing signals 4, wire 21 to the operating box; and (b) to the right in wire 22, wire 23, fire warning signals 2 and 3, wire 24, magnet 6, wire 30 to the operating box; and (2) from the operating box to the right in wire 20, magnet 5, wire 21 to the operating box, where this path joins path (1^a) thence to contact 28, arm 25, spring 13, spring 14 to wire 30—here the paths join and the circuit returns to source 1 through wire 30. On account of the much lower resistance of the path including the resistance 31 and the fire fighting signals 4 the major portion of the total flow from source 1 passes through this path and operates these signals. Signals 2 and 3 being in series with magnet 6 do not receive enough current to operate them.

Station B shows the switch mechanism in such position that the telegraphic transmitting mechanism thereat may cause operation of the fire warning signals and of the fire fighting signals. When the springs 11, 12 and 13, 14 are closed, the circuit from source 1 is to wire 20, to the operating box, where the circuit divides into two paths: (1) from wire 20 to spring 11, spring 12, arm 15, contact 16, to wire 24, which this circuit divides into two paths: (a) to the left in wire 24, to wire 23, fire warning signals 3 and 2, wire 22, fire fighting signals 4, wire 21 to the operating box; and (b) to the right in wire 24, magnet 6, wire 30 to the operating box; and (2) from the operating box to the right in wire 20, magnet 5, wire 21 to the operating box, where this path joins path (1^a) thence to contact 26, arm 25, spring 13, spring 14 to wire 30—here the paths join and the circuit returns to source 1 through wire 30. On account of the much lower resistance of the path including the alarm receiving devices 2, 3 and 4 the major portion of the total flow from source 1 passes through this path and operates these devices.

Station C shows the switch mechanism in such position that the telegraphic transmitting mechanism thereat may cause operation of only the fire warning signals associated with that station. When the springs 11, 12 and 13, 14 are closed, the circuit from source 1 is to wire 20, to the operating box, where the circuit divides into two paths: (1) from wire 20 to spring 11, spring 12, arm 15, contact 19, resistance 32 (which is approximately equal to the total resistance of the devices 4 and the remainder of the devices 3 and 2, and is used in this path as a substitute for them, and in practice could be made approximately equal to resistance 31) to wire 23, where this circuit divides into two paths: (a) fire warning signals 3 associated with the operating box; and (b) to the left in wire 23, fire warning signals 3, wire 24, magnet 6, wire 30 to the

operating box, and (2) from the operating box to the right in wire 20, magnet 5, wire 21, fire fighting signals 4, wire 22, wire 23, fire warning signal 2 to the operating box where this path joins path (1^a) thence to contact 29, arm 25, spring 13, spring 14 to wire 30—here the paths join and the circuit returns to source 1 through wire 30. On account of the much lower resistance of the 10 path including the resistance 32 and the fire warning signals 3 associated with the operating box, the major portion of the total flow from source 1 passes through this path and operates these devices. Devices 15 2 and 4 and the devices 3 associated with other stations being in series with either magnet 5 or magnet 6 are not operated.

Station D shows the switch mechanism in such position that the telegraphic transmitting mechanism thereat may cause operation of the fire warning signals only. When the springs 11, 12 and 13, 14 are closed, the circuit from source 1 is to wire 20, to the operating box, where the circuit 25 divides into two paths: (1) from wire 20 to spring 11, spring 12, arm 15, contact 17, to wire 24, where this circuit divides into two paths: (a) to the left in wire 24, to wire 23, fire warning signals 3 and 2, wire 30 22, to the operating box; and (b) to the right in wire 24, magnet 6, wire 30 to the operating box; and (2) from the operating box to the right in wire 20, magnet 5, wire 21, fire fighting signals 4, wire 22, to the 35 operating box where this path joins path (1^a), thence to contact 27, arm 25, spring 13, spring 14 to wire 30—here the paths join and the circuit returns to source 1 through wire 30. On account of the much lower 40 resistance of the path including the fire warning signals 2 and 3 the major portion of the total flow from source 1 passes through this path and operates these devices. Devices 4 being in series with magnet 5 are 45 not operated.

Since the current in magnets 5 and 6 is at no time interrupted or reversed by the action of springs 11, 12 and 13, 14, it is evident that signals may be transmitted by 50 means of these springs without affecting the device 7. It will also be noticed that the normal current flow in devices 2, 3 and 4 is in the opposite direction to the signaling current which flows through these devices while the springs 11, 12 and 13, 14 are in contact, thus tending to neutralize any residual magnetism which may be 55 present.

I claim:

60 1. In a signaling system, a normally closed circuit, and, in said circuit, a source of current, two sets of signals, and, at each of a plurality of stations, switch mechanism, and telegraphic transmitting mechanism, said switch mechanism having two

contact arms, four contact points for each arm, circuit connections from each contact point, and a yoke insulatingly connecting said arms, said telegraphic transmitting mechanism having two circuit controllers, 70 and mechanism for operating said circuit controllers, and such construction and arrangement of said switch mechanism that when said switch mechanism is in one position at one station operation of the telegraphic transmitting mechanism at that station will result in the action of but one set of said signals.

2. In a signaling system, a normally closed circuit, and, in said circuit, a source 80 of current, two sets of signals, and, at each of a plurality of stations, switch mechanism, and telegraphic transmitting mechanism, said switch mechanism having two contact arms, four contact points for each arm, circuit connections from each contact point, and a yoke insulatingly connecting said arms, said telegraphic transmitting mechanism having two circuit controllers, 85 and mechanism for operating said circuit controllers, such construction and arrangement of said switch mechanism that when said switch mechanism is in one position at one station, operation of the telegraphic transmitting mechanism at that station will result in the action of but one set of said signals, and such construction and arrangement of said switch mechanism that when said switch mechanism is in another position at one station operation of the telegraphic transmitting mechanism at that station will result in the action of the other set of said signals.

3. In a signaling system, a normally closed circuit, and, in said circuit, a source 105 of current, two sets of signals, and, at each of a plurality of stations, switch mechanism, and telegraphic transmitting mechanism, said switch mechanism having two contact arms, four contact points for each arm, circuit connections from each contact point, and a yoke insulatingly connecting said arms, said telegraphic transmitting mechanism having two circuit controllers, and mechanism for operating said circuit controllers, such construction and arrangement of said switch mechanism that when said switch mechanism is in one position at one station operation of the telegraphic transmitting mechanism at that station will result in the action of but one set of said signals, and such construction and arrangement of said switch mechanism that when said switch mechanism is in another position at one station operation of the telegraphic transmitting mechanism at that station will result in the action of the other set of said signals.

110 4. In a signaling system, a normally closed circuit, and, in said circuit, a source of current, two sets of signals, and, at each of a plurality of stations, switch mechanism, and telegraphic transmitting mechanism, 115 said switch mechanism having two contact arms, four contact points for each arm, circuit connections from each contact point, and a yoke insulatingly connecting said arms, said telegraphic transmitting mechanism having two circuit controllers, and mechanism for operating said circuit controllers, such construction and arrangement of said switch mechanism that when said switch mechanism is in one position at one station operation of the telegraphic transmitting mechanism at that station will result in the action of but one set of said signals, and such construction and arrangement of said switch mechanism that when said switch mechanism is in another position at one station operation of the telegraphic transmitting mechanism at that station will result in the action of the other set of said signals.

120 5. In a signaling system, a normally closed circuit, and, in said circuit, a source of current, two sets of signals, and, at each of a plurality of stations, switch mechanism, and telegraphic transmitting mechanism, 125 said switch mechanism having two contact arms, four contact points for each arm, circuit connections from each contact point, and a yoke insulatingly connecting said arms, said telegraphic transmitting mechanism having two circuit controllers, and mechanism for operating said circuit controllers, such construction and arrangement of said switch mechanism that when said switch mechanism is in one position at one station operation of the telegraphic transmitting mechanism at that station will result in the action of but one set of said signals, and such construction and arrangement of said switch mechanism that when said switch mechanism is in another position at one station operation of the telegraphic transmitting mechanism at that station will result in the action of the other set of said signals.

- other position at one station operation of telegraphic transmitting mechanism at that station will result in the action of both sets of said signals.
5. 4. In a signaling system, a normally closed circuit, and, in said circuit, a source of current, fire warning signals, fire fighting signals, and, at each of a plurality of stations, switch mechanism, and telegraphic transmitting mechanism, said switch mechanism having two contact arms, four contact points for each arm, circuit connections from each contact point, and a yoke insulatingly connecting said arms, said telegraphic transmitting mechanism having two circuit controllers, and mechanism for operating said circuit controllers, such construction and arrangement of said switch mechanism that when said switch mechanism is in one position at one station operation of the telegraphic transmitting mechanism at that station will result in the action of only the fire warning signals, such construction and arrangement of said switch mechanism that when said switch mechanism is in another position at one station operation of the telegraphic transmitting mechanism at that station will result in the action of only the fire fighting signals, such construction and arrangement of said switch mechanism that when said switch mechanism is in another position at one station operation of the telegraphic transmitting mechanism at that station will result in the action of both the fire warning signals and the fire fighting signals, and such construction and arrangement of said switch mechanism that when said switch mechanism is in another position at one station operation of the telegraphic transmitting mechanism at that station will result in the action of only the fire warning signals associated with that station.
5. In a signaling system, a normally closed series circuit, and, in said circuit, a source of current, fire fighting signals, fire warning signals, and two series resistances, and, at each of a plurality of stations, switch mechanism, and telegraphic transmitting mechanism, and such construction and arrangement of said switch mechanism that when said switch mechanism is in one position at one station operation of the telegraphic transmitting mechanism at that station will form a multiple circuit connected to said source and having three branches, first, the fire warning signals in series with each other, second, one series resistance in series with the fire fighting signals, and third, the other series resistance.
6. In a signaling system, a normally closed series circuit, and, in said circuit, a source of current, fire fighting signals, fire warning signals, and two series resistances, and, at each of a plurality of stations, switch mechanism, a station resistance, and telegraphic transmitting mechanism, and such construction and arrangement of said switch mechanism that when said switch mechanism is in one position at one station operation of the telegraphic transmitting mechanism at that station will form a multiple circuit connected to said source and having three branches, first, the fire warning signals in series with each other, second, one series resistance in series with the fire fighting signals, and third, the other series resistance.
7. In a signaling system, a normally closed series circuit, and, in said circuit, a source of current, fire fighting signals, fire warning signals, and two series resistances, and, at each of a plurality of stations, switch mechanism, a station resistance, and telegraphic transmitting mechanism, such construction and arrangement of said switch mechanism that when said switch mechanism is in one position at one station operation of the telegraphic transmitting mechanism at that station will form a multiple circuit connected to said source and having two branches, one of said branches comprising the fire fighting signals, the other of said sub-branches comprising the fire warning signals in series with one series resistance, and the other of said branches comprising the other series resistance.
8. In a signaling system, a normally closed series circuit, and, in said circuit, a source of current, fire fighting signals, fire warning signals, and two series resistances, and, at each of a plurality of stations, switch mechanism, a station resistance, and telegraphic transmitting mechanism, such construction and arrangement of said switch mechanism that when said switch mechanism is in one position at one station operation of the telegraphic transmitting mechanism at that station will form a multiple circuit connected to said source and having three branches, first, the fire warning signals in series with each other, second, one series resistance in series with the fire fighting signals, and third, the other series resistance.

- sistance, such construction and arrangement of said switch mechanism that when said switch mechanism is in another position at one station operation of the telegraphic transmitting mechanism at that station will 5 form a multiple circuit connected to said source and having two branches, one of said branches comprising the station resistance in series with two sub-branches, one of said 10 sub-branches comprising the fire fighting signals, the other of said sub-branches comprising the fire warning signals in series with one series resistance, and the other of said branches comprising the other series resistance, and such construction and arrangement of said switch mechanism that when 15 said switch mechanism is in another position at one station operation of the telegraphic transmitting mechanism at that station will 20 form a multiple circuit connected to said source and having three branches, first, the fire fighting signals in series with the fire warning signals, second, one series resistance, and third, the other series resistance. 25 9. In a signaling system, a normally closed series circuit, and, in said circuit, a source of current, fire fighting signals, fire warning signals, and two series resistances, and, at each of a plurality of stations, switch 30 mechanism, two station resistances, and telegraphic transmitting mechanism, such construction and arrangement of said switch mechanism that when said switch mechanism is in one position at one station operation of the telegraphic transmitting mechanism at that station will 35 form a multiple circuit connected to said source and having three branches, first, the fire warning signals in series with each other, second, one series resistance in series with the fire fighting signals, and third, the other series resistance. 40 45 50 55 60 65 and such construction and arrangement of said switch mechanism that when said switch mechanism is in another position at one station operation of the telegraphic transmitting mechanism at that station will 70 form a multiple circuit connected to said source and having two branches, one of said branches comprising the other station resistance in series with two sub-branches, one of said sub-branches comprising the fire 75 warning signals associated with that station, the other of said sub-branches comprising certain fire warning signals in series with one series resistance, and the other of said branches comprising the other series resistance in series with the fire fighting signals and the other fire warning signals. 80 85 90 95 100 105 110 115 120 125 130 135 140 145 150 155 160 165 170 175 180 185 190 195 200 205 operation of the telegraphic transmitting mechanism at that station will result in operation of the fire fighting signals and the fire warning signals by forming a multiple circuit connected to said source and having three branches, first, the fire fighting signals in series with the fire warning signals, second, one series resistance, and third, the other series resistance, and such construction and arrangement of said switch mechanism that when said switch mechanism is in another position at one station operation of the telegraphic transmitting mechanism at that station will result in operation of only the fire warning signals associated with that station by forming a multiple circuit connected to said source and having two branches, one of said branches comprising

the other station resistance in series with two sub-branches, one of said sub-branches comprising the fire warning signals associated with that station, the other of said sub-branches comprising certain of the fire warning signals in series with one series resistance, and the other of said branches comprising the other series resistance in series with the fire fighting signals and other fire warning signals.

In witness whereof, I have hereunto subscribed my name this 10th day of January, 30 A. D., 1914.
